J. S. REID

TANK OR CAN CLOSURE

Filed March 30, 1920

FIG. 1

FIG. 3.

HIGA

James S. Reid

John A. Bonnhardt

HTTP.

UNITED STATES PATENT OFFICE.

JAMES S. REID, OF CLEVELAND, OHIO, ASSIGNOR TO THE EASY-ON CAP COMPANY, CLEVELAND, OHIO, A CORPORATION OF OHIO.

TANK OR CAN CLOSURE.

Application filed March 30, 1920. Serial No. 369,909.

To all whom it may concern:

Be it known that I, JAMES S. REID, a citizen of the United States, residing at Cleveland, in the county of Cuyahoga and State 5 of Ohio, have invented certain new and useful Improvements in a Tank or Can Closure, of which the following is a specification.

This invention relates to closures and has for its object to provide a device of the character stated which is particularly adapted 10 for use in connection with the fuel tanks carried by motor vehicles.

The invention further comprises a closing device which may be quickly and conveniently applied to any standard type of fuel tank without necessitating any changes therein, and it further consists in the provision of a device which may be simply and conveniently removed, and cheap of manufacture. 20

The invention further consists in the certain construction and combination of parts hereinafter illustrated, described and particularly pointed out in the accompanying 25 claim.

Référence is had to the accompanying drawings wherein like reference numerals designate similar parts of reference throughout the various views, and wherein Fig. 1 is 30 a sectional view through the device as it is attached to the fuel tank, the cutting plane being indicated by the line 1—1 of Fig. 2; Fig. 2 is a bottom plan of the device; and Figs. 3 and 4 are detail perspectives showing 35 the cap and bushing adapter as viewed from the bottom.

The invention as shown comprises a fuel tank 1 supplied with the customary internally threaded bushing 2, and said bushing 40 is provided with an annular flange 3 whereby it may be welded or otherwise fixed to said tank. Heretofore a cap or plug has been threaded directly into said bushing to serve as a closure, and as these bushings are 45 usually provided with a fine thread it has been difficult to start the cap therewithout without crossing the threads, this eventually resulting in badly mutilated threads. To overcome this I provide an adapter ring 4 which is formed with a hexagonal flange 5 and which is threaded securely into place 50 within said bushing. This adapter is secured in position with sufficient tightness to

provide a seal and is intended to remain in place at all times. This adapter is provided 55 with a central opening 6 and a pair of diametrically opposed vertical slots or channels 7, and leading from opposite sides of each of said channels are concentric cam faces 8 for a purpose to be hereinafter described. 60 A cap or plug 9 provided with an operating handle 10 and an annular flange 11, in which is placed a sealing gasket 12, is provided to close the opening 6 within the bushing or adapter 4, and said cap has secured to its bottom a leaf spring 14, the ends of which project diametrically beyond the outside edge of the cap for a short distance. The cap is further provided with an air passage 15 by means of which air is allowed to enter 70 the tank and prevent any vacuum therewithin.

In operation and when it is desired to close the opening the cap is so positioned that the extending ends of the spring 14 are 75 in alignment with the vertical channels 7. The cap is then inserted and rotated, causing the ends of the spring to ride up the inclined cam faces 8. As this rotation continues the cap is drawn in to effectively seal the 80 opening, the operation being very similar to that used for the well known bayonet type of joint. And the cap may be very quickly released and lifted out by reverse motion.

It is evident that the above described construction is capable of being modified in various ways and while I have shown and described this particular form I do not wish to be limited in the construction of the same further than is required by the state of the 85 art or that which comes within the scope of the appended claims.

I claim:

In a closure device of the type having a tubular member with spaced recesses and 90 cam portions and a cap member with gasket means for engaging the top portion of the tubular member with sealing effect, an improved cap member provided with a locking member extending across the underside of 100 said cap member and secured thereto, said locking member and cap member being provided with vent means therethrough, said locking means having spaced individually acting spring end portions extending 105 radially outwardly and adapted to enter the

recesses of the tubular member and engage the cam portions thereof upon relative rotation of said cap and tubular members, whereby when the cap member is applied to the 5 tubular member the yielding end portions of the locking means will yield freely and fully and cause the gasket means to be engaged and compressed between the cap member and tubular member with sealing effect but without undue compression of the gasket means. 10 In testimony whereof, I do affix my signature.

JAMES S. REID:
